United States Patent Office

Des. 193,959

Patented Oct. 30, 1962

193,959

FIRE ALARM BOX

Samuel Ayres, Jr., Marblehead, Mass., assignor to The Gamewell Company, Newton Upper Falls, Mass., a corporation of Delaware

Filed July 11, 1961, Ser. No. 65,888

Term of patent 14 years

(Cl. D72—1)

FIG. 1

FIG. 3

FIG. 2

FIG. 4

FIG. 5

The dominant features of my design reside in the portions shown in full lines.

I claim:

The ornamental design for a fire alarm box, as shown and described.
